UNITED STATES PATENT OFFICE.

EDWARD A. SMETZER, OF CLEVELAND, OHIO.

LAMP LIGHTER AND EXTINGUISHER.

1,123,605.

Specification of Letters Patent.

Patented Jan. 5, 1915.

Application filed April 23, 1914. Serial No. 833,957.

To all whom it may concern:

Be it known that I, EDWARD A. SMETZER, a citizen of the United States, residing at Cleveland, in the county of Cuyahoga and State of Ohio, have invented certain new and useful Improvements in Lamp Lighters and Extinguishers; and I do hereby declare the following to be a full, clear, and exact description of the invention, such as will enable others skilled in the art to which it appertains to make and use the same.

This invention relates to lamp lighters and extinguishers, and one of the principal objects of the invention is to provide a device to be connected to a lamp for lighting the wick and for extinguishing the same when desired, said lighter being operated by a finger lever at one side of the device and the extinguisher being operated by another lever of similar character at the opposite side of the device.

Another object of the invention is to provide a lamp lighter of simple construction which will not require the use of matches, which will be safe and reliable in use, and which will be inexpensive to manufacture and which will be always ready on the lamp.

These and other objects may be attained by means of the construction illustrated in the accompanying drawings, in which,

Figure 1 is a side elevation of a lamp lighter and extinguisher made in accordance with this invention. Fig. 2 is a top plan view of the same. Fig. 3 is a detail sectional view taken on the line 3—3 of Fig. 1 looking in the direction indicated by the arrows, and Fig. 4 is a sectional view taken on the line 4—4 of Fig. 3, looking in the direction indicated by the arrow, and made on a larger scale.

Referring to the drawing, the numeral 1 designates the base portion of the lamp lighter and 2 is the base portion of the extinguisher. The base portion 1 is provided with a curved member 3, which is pivoted at 4 to the curved member 5 formed on the base 2 of the extinguisher, and said base portion being provided with a curved clamp member 6 which engages the similar member 7 formed on the base 1 when connected by the adjusting screw 8. The clamp members 6 and 7 engage the neck of a lamp of any suitable structure and the numeral 9 designates the wick of the lamp, said lamp not being shown.

Pivoted at 10 to lugs 11 rising from the

base 1 is a lever 12, said lever having an enlarged finger piece 13. The opposite end of the lever is pivotally connected at 14 to a vertical bar 15, and said bar carries at its upper end a pivoted link 16 having a spring pawl 17 at its outer end, while its inner end is pivoted at 18 to the horizontal arm 19 of a bracket 20 supported upon the base 1. The pawl 17 engages the teeth of a gear wheel 21 journaled in the arm 19, and said gear wheel meshing with a pinion 22 mounted on a shaft 23 at the side of the roughened steel wheel 24. Supported upon the base 1 is a tube 25 in which is placed a stick of sparking composition to be pushed up against the roughened wheel 24 by means of a spring 27, said sparking composition 26 resting on the top of the spring 27 and a set screw 28 extending through the base 1 and having an enlarged head 29 upon which the spring 27 rests, as shown in Fig. 4.

The gasoline or alcohol tube 30 for the lighter is provided with a curved upper end 31 through which the wick 32 extends. For extinguishing the wick of the lighter, a lever 33 is pivoted at 34 to the bracket 20, one end of said extinguisher being connected to a spring 35, while the opposite end of said spring is connected to the link 16. A stop 36 for the end of the extinguisher 33 is connected to the bar 15. The front end 37 of the extinguisher is curved to normally cover the upper end of the wick 32 of the lighter.

The lamp extinguisher comprises a lever 38 pivoted at 39 to a bracket 40 extending from the base 2, said lever being provided with an extinguishing member 41, which is normally held away from the wick 9 by means of a spring 42 connected at one end 95 to the lever 38 and at the opposite end to a bracket 43 formed on the base 2. Pivoted to the bracket 43 is a lever 44, the inner end of which engages an inclined extension 45 on the lever 38 for operating the extinguisher.

The operation of the invention may be briefly described as follows: To light the wick 9, the lever 12 is operated by pressing down upon the finger rest 13, thus operating the wick extinguisher 33 to uncover the wick 32 and rotating the gear wheel 21 and the pinion 22 to rotate the roughened wheel 24 against the igniter 26 to light the wick 32 and project the spark onto the wick 9 to light the lamp. When the finger is removed from the rest 13, the parts assume the posi-

tion shown in Fig. 1 to extinguish the wick 32 and to leave the wick 9 lighted. When it is desired to extinguish the wick 9 the lever 44 is operated.

5 From the foregoing it will be obvious that a lamp lighter and extinguisher made in accordance with this invention may be manufactured at low cost, is simple in construction, is reliable in operation and can be 10 readily connected to any form of a lamp.

Various changes may be made in the details of construction without departing from the spirit and scope of the invention as defined in the claim.

15 What is claimed is:—

A lamp lighter comprising a base, means for securing said base to the neck of a lamp in position to light the wick of the lamp, a lever pivoted to the base, a bracket connect- 20 ed to the base, a gear wheel pivoted to said

bracket, a pawl carried by said lever, a pinion in mesh with said gear wheel, a roughened wheel movable with said pinion, a wick tube having a curved upper end, a wick in said tube, an extinguisher for said wick, 25 said extinguisher having a curved end which normally covers the outer end of the wick, said extinguisher being pivoted to the bracket, a spring for normally holding the said extinguisher in operative position and 30 means whereby the extinguisher is thrown away from the wick when the lighter is operated.

In testimony whereof I affix my signature in presence of two witnesses.

EDWARD A. SMETZER.
